Carlos S. Andrews
by A. Miller Beffier Atty.

UNITED STATES PATENT OFFICE.

CARLOS S. ANDREWS, OF CHICAGO, ILLINOIS.

SCREWDRIVER OR THE LIKE.

1,377,958.

Specification of Letters Patent. Patented May 10, 1921.

Application filed August 28, 1916. Serial No. 117,207.

To all whom it may concern:

Be it known that I, CARLOS S. ANDREWS, a citizen of the United States, residing at Chicago, in the county of Cook and State of Illinois, have invented a certain new and useful Improvement in Screwdrivers or the like, of which the following is a full, clear, concise, and exact description, reference being had to the accompanying drawings, forming a part of this specification.

My invention relates to screw drivers and similar tools.

The principal object of the invention is to provide a screw driver or other similar tool with magnetic qualities so that it can hold a screw or similar article in position to be inserted, and thereby avoid the necessity of holding such article by the fingers.

A further object of the invention is to provide a practical and economic arrangement for providing the magnetic qualities aforesaid.

Other objects of the invention will appear and be set forth hereinafter.

In the accompanying drawings Figure 1 is a longitudinal section of a screw driver embodying my present invention;

Fig. 2 is a longitudinal section on an enlarged scale of a portion of the same;

Fig. 3 is a plan view of such portion;

Fig. 4 is a view of a detail of construction;

Figs. 5 and 6 are views of a modified form of said detail.

In the drawings I show a screw driver having a handle 1 and a shank 2. The handle 1 is preferably made hollow or tubular and contains an electric battery 3. The end 4 of said handle is made detachable as by a screw threaded connection 5 with the main portion of the handle so that said end 4 may be detached to permit the removal of the electric battery 3 and the replacement of the same or of another battery of the same kind. The handle end 4 is provided with a spring 6 by which the battery 3 is pushed normally as far into the handle 1 as possible. The shank 2 is preferably made with an enlarged end 7 which fits into the other end 50 of the handle 1. This end 7 as well as the shank 2 is magnetic material, preferably a low grade steel. A rivet or pin 8 or other suitable device is provided for holding the head 7 firmly in position in the handle. The head 7 is provided with a flange arrange-

ment 9 which fits against the end of the handle 1 so that said head 7 serves as a closure and cover for the end of said handle 1. A coil 10 of fine wire is shown wound about the shank 2 near the head 7. Said coil 10 has 60 a sufficient length of proper sized wire to cause the magnetization of the shank 2 by the battery 3 when the current of said battery is passed through said coil. As a convenient arrangement the coil 10 is made in 65 more or less conical form and is inclosed in a case or sheath 11.

The arrangement is preferably such that the battery 3 may be connected and disconnected with the coil 10 so as to energize 70 and deenergize said coil and thereby magnetize the shank 2 and discontinue the magnetization thereof. As a convenient arrangement and a matter of further improvement the handle 1 is provided with a contact 75 device 12 having a contact surface 13 on the inner side of said handle making contact with the metal sheath 3^a of the battery 3, and thereby with one pole of same. One end 14 of the coil 10 is led to a screw 15 80 which holds another contact plate 16 in position. A metal slide 17 is arranged to slide upon a pin 18 and is so constructed that when shifted to the right, as shown in Fig. 2, it will extend from the contact plate 12 85 to the contact plate 16 and thereby make connection between the same. When, however, said slide 17 is shifted to the left, its right hand end will separate from the contact plate 16, and thereby open the side 90 of the circuit formed by said contact plates and the screw 15 and conductor 14, it being understood that the end of the conductor 14 is well insulated from the head 7, as for example by embedding it in insulating material 95 20. The other side of the circuit is made by connecting the other end 21 of the coil 10 to the metal head 7, said head being in contact with the other pole 22 of the battery 3. Thus it will be seen that by 100 shifting the slide or switch 17 the coil 10 may be energized, thereby magnetizing the shank 2, and by shifting the switch or slide 17 the other way the circuit of the coil 10 will be broken and said coil will no longer 105 be energized. Of course some residual magnetism will remain in the shank 2 for each energization thereof.

Thus it will be seen that by energizing the coil 10 and magnetizing the shank 2, : 1

the latter may be caused to hold a screw 23, as shown in Fig. 1, and the necessity of holding said screw in the hand preparatory to inserting it is avoided. With the screw 5 thus held the screw driver may be turned so as to insert the screw as far as possible.

As a matter of further importance the end 2^a of the shank 2 is preferably enlarged as shown in Fig. 1 and provided with a 10 straight cross face 2^b, which will provide a shoulder or abutment, against which the head of the screw may fit. The blade 24 of the screw driver projects from the shoulder or face 2^b. Thus there is provided a 15 head or end for the shank 2 which will form an enlarged pole for the magnet provided by said shank and will at the same time form a broad surface to secure contact with the entire head of the screw and therefore 20 by prevent the screw from falling or inclining downwardly even though held in position by the magnetism of the shank 2.

In Figs. 5 and 6 I show a modified construction of head 25 having a concave socket 26 to receive the convex head of a screw. The blade 27 is to engage the slot in the screw head as in the other type of device.

It will be understood that while I show the invention as applied to a screw driver, 30 it may also be applied to other kinds of tools.

It will further be understood that changes and modifications may be made without departing from the spirit of the invention.

35 What I claim is:

1. A screw driver having a shank provided with a magnetizing coil and a hollow

handle containing a battery for energizing said coil.

2. A screw driver comprising in combination a tubular handle, a shank having an enlarged end fitting into one end of said tubular handle and forming a closure therefore, an electric battery in said handle and a magnetizing coil on said shank. 40

3. A screw driver comprising a shank provided with a magnetizing coil, and a hollow handle containing a battery, said shank having an enlarged end for engagement with a screw. 45

4. A screw driver comprising a shank provided with a magnetizing coil, and a hollow handle containing a battery, said shank having an enlarged end for engagement with a screw, said enlarged end having a broad 55 face for engagement with the entire surface of the screw head, and a blade projecting from said surface.

5. A screw driver comprising a hollow handle containing an electric battery, one 60 end of said handle being removable to permit removal of the battery, a shank having an enlarged head fitting into and closing the other end of said handle, a coil surrounding the end of said shank nearest said handle, said coil being in conical form, and a conical sheath over said coil. 65

In witness whereof, I hereunto subscribe my name this 30th day of March, A. D. 1916.

CARLOS S. ANDREWS.

Witnesses:

A. LYDA JONES,
HAZEL A. JONES.
